UNITED STATES PATENT OFFICE

2,493,121

UMBRELLA

Johnstone Dean Ellis, Troy, Ohio, assignor to The Troy Sunshade Company, Troy, Ohio, a corporation of Ohio

Application February 16, 1949, Serial No. 76,789

7 Claims. (Cl. 135—20)

1

This invention relates to umbrellas, and more particularly to umbrellas adapted for use on tractors and the like.

It has been found desirable in connection with the use of tractor umbrellas to construct the standard of the umbrella with a portion laterally offset from the main portion of the standard in order to provide for supporting the umbrella cover or canopy in approximately centered position over the head of the user and thus to obtain maximum protection from a cover of given diameter. However, with the conventional umbrella top construction, this offset portion of the standard would interfere with proper closing of the cover unless the latter is positioned at such height above the offset portion as to clear it when closed, and this arrangement would be unsatisfactory from the standpoint of appearance as well as protection to the user.

It is accordingly a principal object of the present invention to provide an umbrella suitable for use on tractors and embodying an offset standard and a top or canopy assembly of simple construction which is separate from the standard when closed and which is adapted to be quickly and easily mounted on the standard as it is opened and to be supported in open position in desired close and centered relation with the head of the user.

An additional object is to provide such an umbrella wherein the handle tube to which the ribs and cover are secured is relatively short for complete disengagement from the runner when the cover is closed, and wherein the offset portion of the standard has an upwardly projecting end piece which is received within the runner and handle tube when the cover is open and is releasably locked to the handle tube above the runner to support the top assembly in open position.

Other objects and advantages of the invention will be apparent from the following description, the accompanying drawings and the appended claims.

In the drawings—

Fig. 1 is a perspective view showing a tractor equipped with an umbrella constructed in accordance with the present invention;

Fig. 2 is a somewhat diagrammatic side view of the upper part of the umbrella, with the cover opened and partly broken away to show the internal construction;

Fig. 3 is a view similar to Fig. 2 showing the cover closed and the top assembly removed from the standard;

Fig. 4 is a fragmentary sectional view on a

2

larger scale showing the parts of the top and standard which interlock when the cover is open; and

Fig. 5 is a detail view showing the bracket for attaching the umbrella standard to the tractor seat.

Referring to the drawings, which illustrate a preferred embodiment of the present invention, the umbrella top assembly is indicated generally

10 at 10, and the supporting standard includes a main upright portion 11, a laterally offset portion 12 at the upper end of the main portion 11, and an upwardly turned elbow portion 13 at the outer end of the offset portion 12. A short tube 15 is formed with a curved lower portion 16 which is inserted within the elbow 13 and is preferably brazed or otherwise secured thereto, and the upper end of elbow 13 is flared outwardly to form a circumferential shoulder 17.

20 The top assembly 10 includes a handle tube 20 of such inner diameter as to receive insert tube 15 readily therein and having secured to the upper end thereof the notcher 21 which receives the hooked inner ends of the ribs 22, and the fabric cover 25 is secured to the upper end of tube 20 between the notcher plate 26 and top cap 27. Braces 28 are pivoted at their outer ends to ribs 22, and their inner ends are pivoted to the runner indicated generally at 30, which includes a runner

30 barrel 33, a runner crown 34 and a runner ring 35.

As shown in Fig. 1, the standard portion 11 is so mounted on the tractor 40 that the elbow 13 is positioned approximately directly over the head of the operator. For example, the standard portion 11 may be clamped in a bracket 42 (Fig. 5) which is bolted between the tractor seat 44 and its supporting member 45. With the standard constructed as shown, the offset portion 12 would interfere with the closing of a conventional umbrella top (carried by the insert tube 15) unless the top were supported at such height above the offset as to receive the full length of the ribs. It will be readily seen that this construction would be unsatisfactory in appearance and would also result in giving very limited protection to the driver of the tractor.

In order to provide for positioning the cover 25 in close proximity to the head of the tractor driver, the handle tube 20 is made relatively short, its length being substantially less than the combined length of one of braces 28 plus the length of the rib portion 22 between the upper end of the brace and the notcher, so that when the umbrella is closed as shown in Fig. 3, the runner 30 is completely disengaged from tube 20. In order to

mount the top assembly on the standard, the insert tube 15 is provided with a latch member or plunger 50, which is carried by a spring 51 mounted within tube 15 on a rivet 52 extending across the inside of the tube. The plunger 50 extends outwardly of tube 15 at a position spaced above shoulder 16 by a distance slightly greater than the axial length of runner barrel 33, and tube 20 is provided with a hole 55 in the side thereof for receiving plunger 50.

With this construction, the umbrella top is completely removed from the standard when closed and is opened while it is being mounted on the standard. In order to open and mount the umbrella top, it is first opened while separated from the standard at least sufficiently to clear the offset standard portion 12, in order to permit mounting of runner 30 on the insert tube 15, and it will usually be found easier to open it sufficiently to slide runner 30 over the lower end of tube 20. The runner and tube 20 are then both slipped over the upper end of tube 15, with the hole 55 in proper angular alignment to receive plunger 50. It will be noted that the upper surface 56 of the plunger is beveled so that it acts as a cam when contacted by the lower ends of the runner and the tube 20, forcing the plunger inwardly and thus permitting the runner and handle tube to move downwardly on tube 15 until their lower ends seat on shoulder 17. The parts are so proportioned that when the runner and handle tube are thus seated as shown in Fig. 4, the hole 55 in tube 20 will be at the proper height to permit the plunger to spring outwardly and lock therein, and thus if tube 20 is in such angular relation with tube 15 that plunger 50 and hole 55 are not in register, the top assembly can be easily rotated while supported on shoulder 17 until the plunger and hole are brought into register.

It will be seen by reference to Figs. 2 and 4 that when the umbrella top is thus mounted on the standard, it is seated on and supported by the shoulder 17, with the handle tube 20 locked to insert tube 15 by the plunger 50. In addition, the plunger 50 is of sufficient length to extend outwardly of tube 20 above the runner 30 to limit upward movement of the runner, satisfactory results having been obtained with a working clearance 57 (Fig. 4) between these parts of the order of $\frac{1}{2}$ to $\frac{3}{4}$ inch, thus effectively preventing undue upward movement of the runner such as might occur under wind gust conditions. It will also be seen that this construction of the umbrella provides for positioning the cover in close relation to the head of the tractor driver, since the total length of the handle tube 20 is only just enough to provide for mounting the runner thereon in the proper spacing from the top of the tube to maintain the ribs and cover in the desired open position. Closing of the umbrella top is also quick and simple with this construction, since it is necessary merely to press the plunger 50 inwardly sufficiently to permit handle tube and runner to be lifted from the insert tube 15, after which the top may be folded in the usual manner.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. An umbrella of the character described comprising a standard including a main supporting

portion having a laterally offset portion and an upper portion extending upwardly from said offset portion, a top assembly separate from said standard and including a handle tube and ribs pivoted to the upper end of said tube, a cover supported by said ribs, braces pivoted to said ribs, a runner pivoted to said braces and adapted for sliding movement on said tube to open and close said cover, said tube and runner being adapted to be received over said upper portion of said standard, a shoulder on said upper standard portion spaced below the upper end thereof to form a seat for the lower end of said runner, and cooperating latch means carried by said upper standard portion above said shoulder and by said tube for releasably locking said tube to said upper standard portion to secure said top assembly to said standard with said cover open, said latch means projecting outwardly of said tube to limit upward movement of said runner on said tube when said umbrella is open.

2. An umbrella of the character described comprising a standard including a main supporting portion having a laterally offset portion and an upper portion extending upwardly from said offset portion, a top assembly separate from said standard and including a handle tube and ribs pivoted to the upper end of said tube, a cover supported by said ribs, braces pivoted to said ribs, a runner pivoted to said braces and adapted for sliding movement on said tube to open and close said cover, said tube being substantially shorter than the combined length of one of said braces plus the rib portion between said tube and the upper end of said brace to provide for complete disengagement of said runner from said tube when said cover is closed, said tube and runner being adapted to be received over said upper portion of said standard, a shoulder on said upper standard portion spaced below the upper end thereof to form a seat for the lower end of said runner, and latch means for releasably locking said tube to said upper standard portion above said shoulder to secure said top assembly to said standard with said cover open.

3. An umbrella of the character described comprising a standard including a main supporting portion having a laterally offset portion and an upper portion extending upwardly from said offset portion, a top assembly separate from said standard and including a handle tube and ribs pivoted to the upper end of said tube, a cover supported by said ribs, braces pivoted to said ribs, a runner pivoted to said braces and adapted for sliding movement on said tube to open and close said cover, said tube being substantially shorter than the combined length of one of said braces plus the rib portion between said tube and the upper end of said brace to provide for complete disengagement of said runner from said tube when said cover is closed, said upper standard portion being of substantially less height above said offset portion than the length of said ribs to prevent closing of said cover when said top assembly is mounted thereon, said tube and runner being adapted to be received over said upper portion of said standard, a shoulder on said upper standard portion spaced below the upper end thereof to form a seat for the lower end of said runner, and latch means for releasably locking said tube to said upper standard portion above said shoulder to secure said top assembly to said standard with said cover open.

4. An umbrella of the character described comprising a standard including a main supporting

portion having a laterally offset portion and an upper portion extending upwardly from said offset portion, a top assembly separate from said standard and including a handle tube and ribs pivoted to the upper end of said tube, a cover supported by said ribs, braces pivoted to said ribs, a runner pivoted to said braces and adapted for sliding movement on said tube to open and close said cover, said tube and runner being adapted to be received over said upper portion of said standard, a shoulder on said upper standard portion spaced below the upper end thereof to form a seat for the lower end of said runner, a latch member projecting outwardly from said upper standard portion and movable inwardly thereof, means biasing said latch member in an outward direction, said latch member being spaced above said shoulder by a distance at least equal to the axial length of said runner, said tube having a hole therein arranged to receive said latch member therethrough when said tube is mounted on said upper standard portion, and said latch member when in latching position extending outwardly of said tube a sufficient distance to intercept and limit upward movement of said runner on said tube.

5. An umbrella of the character described comprising a standard including a main supporting portion having a laterally offset portion and an upper portion extending upwardly from said offset portion, a top assembly separate from said standard and including a handle tube and ribs pivoted to the upper end of said tube, a cover supported by said ribs, braces pivoted to said ribs, a runner pivoted to said braces and adapted for sliding movement on said tube to open and close said cover, said tube and runner being adapted to be received over said upper portion of said standard, a shoulder on said upper standard portion spaced below the upper end thereof to form a seat for the lower end of said runner and for the lower end of said tube, and cooperating latch means carried by said upper standard portion and said tube arranged for interlocking engagement when said tube is seated on said shoulder to secure said top assembly to said standard with said cover open.

6. An umbrella of the character described comprising a tubular standard including a laterally offset portion terminating in an upwardly turned elbow, a tube inserted in the upper end of said elbow and extending upwardly therefrom, a top

assembly separate from said standard and including a handle tube and ribs pivoted to the upper end of said handle tube, a cover supported by said ribs, braces pivoted to said ribs, a runner pivoted to said braces and adapted to be slidably received over said tube to open and close said cover, said parts of said top assembly being so proportioned and arranged that said cover is fully open when the lower ends of said handle tube and said runner substantially coincide, said handle tube and runner being adapted to be slidably received on said insert tube, the upper end of said elbow being flared outwardly to form a shoulder adapted to receive the lower ends of said runner and handle tube, and cooperating means carried by said tubes for releasably interlocking said tubes and said runner to secure said top assembly to said standard with said cover open.

7. An umbrella of the character described comprising a tubular standard including a laterally offset portion terminating in an upwardly turned elbow having the upper end thereof flared outwardly to form a shoulder, a top assembly separate from said standard and including a handle tube and ribs pivoted to the upper end of said handle tube, a cover supported by said ribs, braces pivoted to said ribs, a runner pivoted to said braces and adapted to be slidably received over said tube to open and close said cover, an insert tube including a curved portion fitting within said elbow and secured therein, the upper portion of said insert tube being straight and extending upwardly beyond said shoulder, said runner and handle tube being adapted to be slidably received on said straight portion of said insert tube and to seat on said shoulder, a latch member mounted in said straight portion of said insert tube adjacent the upper end thereof, and said handle tube having a hole therein adapted to receive said latch member to secure said top assembly on said standard with said cover open.
